G. M. BICKNELL

CARBURETOR

Filed July 25, 1921

FIG. 1

FIG. 2

FIG. 3

INVENTOR
GEORGE M. BICKNELL
By Edward G. Longman
ATTY.

UNITED STATES PATENT OFFICE.

GEORGE M. BICKNELL, OF ST. LOUIS, MISSOURI.

CARBURETOR.

Application filed July 25, 1921. Serial No. 487,222.

To all whom it may concern:

Be it known that I, GEORGE M. BICKNELL, a citizen of the United States, and resident of the city of St. Louis and State of Missouri, have invented certain new and useful Improvements in Carburetors, of which the following is a specification, containing a full, clear, and exact description, reference being had to the accompanying drawings, forming a part hereof.

My invention relates to improvements in carburetors, and has for its primary object the provision of a carburetor which is so constructed as to secure a more accurate adjustment of the mixture at idle engine speed.

A further object is to construct a carburetor which can be so adjusted as to secure a uniform and even mixture at the initial throttle openings and before the main nozzle is brought into action.

A still further object is to construct a carburetor in which a separate fuel nozzle and adjustable passage are used for idling the engine and during the initial throttle openings.

In the drawings—

Fig. 1 is a vertical cross sectional view of my improved carburetor.

Fig. 2 an enlarged fragmental portion of the idler tube inlet.

Fig. 3 an enlarged fragmental section of the upper portion of the carburetor showing the idler tube inlet, throttle valve and the regulating screw.

In the construction of my device I employ a carburetor having a casing 4 having an integrally formed float chamber 5 and in this float chamber is mounted the usual float and needle valve 6. Formed integrally within the casing 4 is an air inlet 7 and a mixing chamber 8. Below the mixing chamber 8 and secured within the casing 4 is a choke or venturi 9 into which the main fuel nozzle 10 extends. The lower end of the fuel nozzle opening into the well 11. This well communicates with the passage 13 opening into the float chamber 5. The passage 13 is provided with a calibrated plug 14 which regulates or prevents too rapid a flow of fuel into the well 11. Formed in the wall of the casing and between the main nozzle 10 and the float chamber 5 is a fuel passage 15. This fuel passage way conducting fuel to the engine at idle and initial throttle openings. The lower end of the

passage 15 opens into the passage way 12 and is provided with a calibrated plug 16 which retards the flow of fuel into the passage way 15. The upper end of the passage 15 communicates with the opening 17. A portion of this opening is screw threaded to receive the adjusting screw 18, which adjusting screw is provided with a reduced portion 19 which fits into the opening or port 20. This opening or port furnishes communication with the passage 15 and with the suction chamber 21 of the carburetor. This port is preferably elongated in form as illustrated in Fig. 2. Mounted immediately above the mixing chamber 8 is a throttle valve 22 which is so arranged that when it is closed, it extends across the port 20, so that a portion thereof will be above the valve and a portion below, in other words, divide the port into two portions. Formed through the venturi and communicating with the passage 15 is a by-pass 23. This by-pass is so located that it will always be above the fuel level.

The operation of my device is as follows:

After the carburetor has been connected up and proper fuel connections made, the engine is cranked. When the engine commences to run, the throttle valve is shut off as indicated in Figs. 1 and 3 and the adjusting screw 18 is then screwed outward or inward until the desired quantity of idling mixture is obtained. This movement of the screw is to adjust the size of the passage 24 between the edge of the throttle valve 22 and the projection 19 formed on the screw 18. As the engine operates a certain amount of air is drawn through the by-pass 23 which is a short distance above the fuel level and consequently will create a partial vacuum and pick up fuel and carry it to the opening 22, then through the passage 24 into the suction chamber 21. This picking up of fuel is also assisted by the air passing around the valve 22 in the mixing chamber entering the port 20 and passing through the passage 24. The amount of mixture admitted is regulated by the size of the passage 24, which size is governed by the reduced portion of the screw 18. It is possible, by advancing the screw 18 far enough, to close off the upper portion of the mixing chamber entirely when the throttle valve is closed, but it is preferable in practice to have the screw 18 backed out far enough so that the engine

will run slowly when the valve 22 is entirely closed or in its idling position. The adjustment of the screw 18 also regulates the amount of fuel mixture supplied during 5 the initial throttle opening, or until the main nozzle goes into action. In this way it is possible to throttle the engine so that the automobile can be run at a very slow speed.

10 While I have shown my device as attached to a carburetor having a single main nozzle, it is obvious that my construction can be adapted to any plain tube type of carburetor now commercially used, without 15 departing from the spirit of my invention.

Having fully described my invention, what I claim is:

1. In a carburetor, a casing having a mixing chamber and a suction chamber, a 20 throttle valve located between said chambers, a port formed in the side wall of said casing, said port being of greater diameter than the thickness of the throttle valve and adapted to be bisected thereby 25 when the valve is closed, whereby an unobstructed passage way between the mixing and suction chambers is formed, a fuel passage formed in the wall of said casing and communicating with said port, and 30 means extending into said port and adapted to be moved toward and from the throttle valve for varying the size of said unobstructed passage way adjacent the suction chamber, whereby the amount of fuel and 35 air entering the suction chamber through said passage when the valve is closed, is regulated.

2. In a carburetor, a casing having a mixing chamber and a suction chamber formed therein, a throttle valve located in said casing between said chambers, a port formed 40 in the side wall of said casing at the point of communication between said chambers, said port being of greater diameter than the thickness of the throttle valve and adapted to be bisected thereby when the 45 valve is closed, whereby constant communication between the mixing and suction chambers is maintained, a fuel passage formed in the wall of said casing and communicating with said port, a screw located 50 in said casing, said screw provided with a reduced cylindrical end adapted to be extended into said port along the upper portion thereof and be moved to and from 55 the edge of the valve when the same is closed, whereby the size of the passage way leading into the suction chamber is varied.

3. In a carburetor a casing provided with a port in its side wall, means for supplying a mixture of fuel and air to said port, a throttle valve mounted in said casing and adapted to intersect the port when closed, an adjusting screw carried by said casing, said adjusting screw being provided with a cylindrical end adapted to extend into the port whereby the size of the port may be varied by adjusting the cylindrical end to and from the throttle valve when the same is closed.

In testimony whereof, I have signed my 70 name to this specification.

GEORGE M. BICKNELL.
